Z. PARKHURST.
MACHINE FOR BURRING AND CLEANING WOOL.

No. 94,437.

Patented Aug. 31, 1869.

United States Patent Office.

ZIBA PARKHURST, OF MILFORD, MASSACHUSETTS.

Letters Patent No. 94,437, dated August 31, 1869.

IMPROVEMENT IN MACHINE FOR BURRING AND CLEANING WOOL.

The Schedule referred to in these Letters Patent and making part of the same.

To all persons to whom these presents may come:

Be it known that I, ZIBA PARKHURST, of Milford, in the county of Worcester, and State of Massachusetts, have made a new and useful invention, having reference to Machinery for Burrting, Cleaning, and Carding Wool; and I do hereby declare the same to be fully described in the following specification, and represented in the accompanying drawings, of which—

Figure 1 is a top view,

Figure 2, a side elevation,

Figure 3, a rear-end view, and

Figure 4, a longitudinal section of the machine containing my invention.

In such drawings—

A denotes the frame of the machine, it being provided at its rear end with a receiving-mouth, *a*, a pair of feed-rollers, *b b*, and a "burr-box," *c*, the said burr-box being disposed, with respect to the first or receiving-card cylinder *B*, in manner as represented.

Within the burr-box, and at its front part, I arrange what I term a "rotary transfferer," *C*, which consists of a horizontal shaft, *d*, provided with a series of blades or wings, *e e e*, extended from it radially, every other one of them being serrated on its outer edge.

A top view of this transfferer is shown in Figure 5, it being put in revolution by an endless belt going around its shaft, or a pulley fixed thereon.

The transfferer, while in operation, serves to intercept the loose fibres which may be passing over the top of the upper feed-roller, and to transfer them to the receiving-cylinder.

It also answers to stir up and open the wool on the receiving-cylinder, during the transit of such wool from the feed-rollers to a rotary beater, *D*, which is arranged directly over the card-cylinder, and on a horizontal shaft, *f*.

This beater consists of a series of rectangular wings, radiating from the said shaft.

The beater is to be put in revolution by any proper means, its purpose being to remove from the wool, on the cylinder *B*, such of the burrs or other extraneous matters as may project beyond the teeth of the cylinder and be carried around within the path of revolution of the said beater.

In advance of the receiving-cylinder *B*, is another such card-cylinder, *F*, which I term a "tumbler."

Arranged between the said two cylinders, in manner as represented, is a series of ribs, *h h*, which are disposed parallel to each other, and obliquely, on a stationary cross-bar, *G*, in manner as shown in top view in Figure 6.

The purpose of these ribs is to stop the waste wool that may fall from the bite of or between the two cylinders *B* and *E*, so that such wool may be caught up by the advanced one.

They also operate to remove the dirt and extraneous matters from the wool beaten against them by the cylinders.

The slanting position of each of the ribs causes it to operate to good advantage for the purposes as mentioned, and to clear itself of the dirt.

In advance of the cylinder or tumbler *F* is the main card-cylinder *H*, and there is arranged between the two, in manner as represented, a stripper or other card-cylinder, *I*, whose purpose is to catch the waste wool which may fall from the cylinder or tumbler *F*, and transfer it to and lay it upon the main cylinder *H*.

In front of the said main cylinder is a doffer card-cylinder, *K*, between which and the main card-cylinder is another series of oblique ribs, *h'*, which are fixed upon a bar, *G'*, the arrangement of them, relatively to the cylinder *H*, being in manner as represented.

The direction of revolution of each of the rotary parts of the said machine is indicated on it by an arrow.

Underneath the cylinder *F* is a rotary beater, *L*, substantially like the beater *D*.

Furthermore, there is another such beater, *M*, arranged underneath, and so as to operate with the main card-cylinder *H*, the whole being as represented.

These beaters are for the removal of the burrs and waste matters from the cylinders *F* and *H*, and also for beating up to them the loose fibres of wool which may project from them.

If desirable, there may be a series of the oblique ribs, arranged directly under the transfferer *C*, or between such and the upper feed-roller.

The revolving parts of the machine are to be provided with suitable mechanism for putting them in revolution, as may be required.

The wool, in going through the machine, will be burred, cleaned, and doffed, it being understood that it is to be removed from the doffer by a comb, such as is in use in ordinary carding-engines.

In such machine I make no claim to the combination of the feed-rollers *b b* and the card-cylinders *B*, *F*, *I*, *H*, and *K*, such being used in machines of like character and purpose.

What I do claim as of my invention is as follows, viz:

1. The arrangement of the rotary transfferer *C* with the burr-box *c*, the feed-rollers *b b*, and the receiving-cylinder *B*.

2. The arrangement of the beater *D*, the receiving-cylinder *B*, the feed-rollers *b b*, the burr-box *c*, and the transfferer *C*.

3. The combination and arrangement of a series of oblique ribs, (as shown at *h* or *h'*, and as above described,) with the receiving-cylinder *B* and the tumbler *F*, or with the card-cylinder *H* and doffer *K*, the whole being substantially as and to operate as specified.

4. The combination and arrangement, as described, of either or both the rotary drums *L M*, with the card-cylinders *F* *I* *H*, and the two series of oblique ribs, the feed-rollers, burr-box *c*, and receiving-card cylinder *B*, substantially as specified.

Witnesses:

R. H. EDDY,
SAMUEL N. PIPER.

ZIBA PARKHURST.
